UNITED STATES PATENT OFFICE.

ORIN A. HANFORD, OF ROCHESTER, NEW YORK, ASSIGNOR TO JOHN L. KELLOGG, OF BATTLE CREEK, MICHIGAN.

PACKAGING-MACHINE.

1,091,509.

Specification of Letters Patent. Patented Mar. 31, 1914.

Application filed January 18, 1913. Serial No. 741,792.

To all whom it may concern:

Be it known that I, ORIN A. HANFORD, a citizen of the United States, residing at Rochester, New York, have invented certain new and useful Improvements in Packaging-Machines, of which the following is a specification.

This invention relates to improvements in packaging machines.

10 The main objects of this invention are, first, to provide an improved packaging machine by which articles of the character of shredded wheat biscuits or other articles of a more or less friable nature may be effectively packed without injury thereto. Second, to provide an improved packaging machine which is automatic in its operations and of large capacity. Third, to provide in a structure of the class described, improved 15 carton feeding means. Fourth, to provide in a structure of the class described, an improved means for filling and discharging the filled cartons. Fourth, to provide an apparatus of the class described, which is comparatively simple in structure and not likely 20 to get out of repair.

Further objects, and objects relating to structural details, will definitely appear from the detailed description to follow.

25 I accomplish the objects of my invention by the devices and means described in the following specification.

The invention is clearly defined and pointed out in the claims.

30 A structure which is a preferred embodiment of my invention is clearly illustrated in the accompanying drawing forming a part of this specification, in which:

Figure I is a side elevation of a structure 35 embodying the features of my invention, the outer ends of the several conveyers being broken away. Fig. II is a plan view partially in horizontal section, on a line corresponding to line 2—2 of Fig. I. Fig. III is a detail plan view of the carton feeding mechanism, the parts removed by the sectioning in Fig. II being here shown. Fig. IV is a transverse vertical section on a line corresponding to line 4—4 of Fig. I, showing 40 details of the article feeding mechanism. Fig. V is a vertical transverse section on a line corresponding to line 5—5 of Fig. I, showing further details of the article feeding mechanism. Fig. VI is a detail vertical 45 section on a line corresponding to line 6—6

of Fig. IV, showing the packer actuating cam 49. Fig. VII is a detail vertical section on a line corresponding to line 7—7 of Fig. V showing the table actuating cam 35. Fig. VIII is a detail vertical transverse section 50 on a line corresponding to line 8—8 of Fig. I, showing features of the holders and cartons feeding mechanism. Fig. IX is a detail vertical transverse section on a line corresponding to line 9—9 of Fig. I, showing details of 55 the carton feeding mechanism. Fig. X is a detail horizontal section on a line corresponding to line 10—10 of Fig. IX. Fig. XI is a detail vertical section on a line corresponding to line 11—11 of Fig. IX, showing 60 details of the carton flap spreading mechanism. Fig. XII is a detail vertical longitudinal section on a line corresponding to the broken line 12—12 of Fig. III, showing 65 further details of the carton feeding mechanism. Fig. XIII is a detail vertical transverse section on a line corresponding to line 13—13 of Fig. XII. Fig. XIV is a detail 70 vertical transverse section on a line corresponding to line 14—14 of Fig. III showing 75 details of the carton feed table. Fig. XV is a detail section on a line corresponding to line 15—15 of Fig. I, showing details of the 80 packing mechanism and the means for discharging the cartons. 85

In the drawing similar reference characters refer to similar parts throughout the several views, and the sectional views are taken looking in the direction of the little arrows at the ends of the section lines. 90

Referring to the drawing, the frame 1 is shown mainly in conventional form and may be of any desired construction to properly support the parts and their driving connections. 95

The driving shaft 2 is driven by the pulley 3 and the driving belt 4. The articles to be packaged are conveyed to the machine on trays 5 by the conveyer or feed belt 6. The trays are returned or discharged from the machine by the conveyer 7. The empty cartons are carried into the machine by the conveyers 8 while the filled cartons are carried from or discharged from the machine by the conveyer 9. The outer ends of these conveyers are not illustrated as the means for delivering the filled trays to the conveyers 6 or the unsealed cartons to the conveyers 8 or for handling the filled cartons from no part of this invention. In practice, the filled 100

105

110

- cartons are preferably delivered to the conveyers 8 from a suitable bottom sealer and from the conveyer 9 to a top sealer.
- The conveyer 6 is driven by the shaft 10 provided with a suitable roller or pulley 11. The shaft 10 is connected by the gears 12 and 13 to a shaft 14. The shaft 14 is connected by the sprocket chain 15 to a shaft 16 disposed toward the bottom of the frame.
- 10 The shaft 16 is connected by the sprocket chain 17 to a shaft 18 extending across the frame. The shaft 18 is in turn connected on the opposite side of the machine by the sprocket chain 19 to the driving shaft 2.
- 15 The several sprocket wheels are not designated by numerals as their arrangement will be readily understood. Other parts are driven through this connection as will appear as the description proceeds.
- 20 The trays 5 are provided with flanges 20 on their longitudinal edges. The trays are delivered from the feed conveyer 6 onto the table 21 by a mechanism consisting of the sprocket chains 22 having flight-like pusher bars 23 mounted thereon. The sprocket chains 22 are supported to travel above and parallel with the inner end of the conveyer 6 by means of sprocket wheels 24 and 25 carried by a shaft 26 and the shaft 14 respectively, the sprockets 25 being the driving sprockets. As the flights or pushers 23 are carried along by the sprocket chains, they engage the rear ends of the trays 5 and push them from the inner end of the conveyer 6 onto the table 21. As the trays are pushed onto this table, the biscuits or other articles to be packaged, carried by the trays, are picked up by the scoop or pick-up 27 which is disposed above the table and in proper spaced relation thereto, so that the tray passes under the scoop and the articles onto it. The structure illustrated, is designed for simultaneously filling two series of cartons.
- 45 The scoop is provided with diverging chutes 28 at its rear end. See Figs. II, IV, and V. The scoop is flanged at its edges to retain and guide the articles thereon. The structure illustrated, is especially designed for the packaging of shredded cereal biscuits which are placed on the trays in two rows. The trays are in practice preferably baking trays so that the biscuits are packaged direct from the ovens without handling. The flights or pushers 23 engaging the rear ends of the trays, serve to support the biscuits as well as to carry the trays along so that the biscuits are delivered onto the scoop as described.
- 55 The table 21 is provided with a guide flange 29 at one side. This table 21 is pivoted at 30 and is supported in its operative position by means of the link 31 mounted on the slide 32. This slide 32 travels in the vertical slide-way 33 as shown in Fig. V.

As the structural details of this slide and slide-way are not a part of this invention they are not here shown. The slide 32 is provided with a roller 34 traveling on the cam 35 on the shaft 16. As the cam revolves, the roller 34 drops into the low point 36 of the cam, allowing the table to tilt or swing down on its pivot, discharging the empty tray onto the tray return conveyer 7. This operation is timed and the cam is shaped so that the table is swung up to operative position to receive the succeeding tray. The articles are delivered from the chutes 28 into the holders or packing receptacles 37. These holders or receptacles 37 are carried by arms 38 radially mounted on the shaft 39, the structure illustrated being provided with a double series of four holders each.

The arms 38 carrying the holders, are connected by braces 40. See Fig. I. The shaft 39 is driven intermittently through a Geneva stop gear 41 on the shaft 39 and the coacting gear 42 and arm 43 on the shaft 44. The shaft 44 is connected by the sprocket chain 45 to the shaft 16 which is driven through the connections previously pointed out. As the details of the driving connections for the shaft 44 to the holder carrying shaft 39 do not form a part of this present invention, I do not describe the same with further detail herein, the object of this type of driving connection being to drive the shaft 39 with a step by step movement properly timed to bring the holders 37 into position to receive the articles as they are delivered from the chutes 28.

The articles are delivered from the chutes 28 into the holders by the packers 46 supported on the arms 47 on the rock shaft 48 extending across the frame above the chutes. The packers 46 are actuated from the cams 49 on the shaft 14. The cams 49 act upon the reciprocating rods 50 supported in suitable bearings in the brackets 51. The rods 50 are connected to levers 52 on the shaft 53, the levers being connected by the links 54 to the arms 47 of the packers. The cams 49 are provided with a plurality of cam projections 55, (see Fig. VI), there being twelve of these projections on the cams of structure illustrated, so that each package contains twelve articles. The rods 50 are provided with rollers 56 traveling on the cams.

To support the articles in proper position as they are being packed in the holders 37, and also to eject them into the cartons and the cartons from the holders, I provide the holders with plungers 57 supported by the stems 58 reciprocating in suitable sleeves 59 within the holder carrying arms 38. The plungers are yieldingly supported by the coiled springs 60 arranged within the sleeves. The plungers are provided with racks 61 with which the pawls 62 coact. See 180

Fig. XV. These pawls 62 are provided with actuating springs 63. As the articles are packed into the holders by the packers 46, the plungers are forced inwardly against the tension of the springs 60 and are retained by the pawls until released by the pawl trips 64 which are positioned to act after the cartons have been slipped over the holders so that the articles are delivered into the cartons. This step in the cycle of operations of the machine will be again referred to in its proper sequence.

The shaft 39, is, as stated, actuated with a step by step movement, each step being a quarter revolution of the shaft. From the filling position, the holders are actuated to a vertical position to receive the cartons 65 which are slipped over the holders.

The cartons are, as stated, conveyed to the machine by the conveyers 8, the cartons being arranged on the conveyers on their sides with their open ends facing inwardly. The conveyers 8 are driven through the sprocket chains 134 connecting them to the shaft 2. The cartons are carried by the conveyers 8 against the stops 66. From these conveyers 8, the cartons 65 are delivered or shifted onto the feed table 67 which projects forwardly so that the holders 37 swing under its forward end when they are brought to the vertical position from their filling position.

The carton shifter members 68 are provided with fixed fingers 69 at their outer ends adapted to engage the outer ends of the cartons and pivoted plate-like clamping fingers 70 adapted to engage opposite sides thereof. The clamping fingers or plates 70 are mounted on the pivots 71 on the arm 72 on the member 68. Springs 73 support the clamping fingers 70. The member 68 is arranged upon a spindle 74 carried by an oscillating member 75 mounted on the shaft 76. The oscillating member 75 is provided with a segment 77 which is actuated by the rack 78 arranged in a vertically disposed slide bearing member 79, see Fig. IX. The rack 78 is connected by the link 80 to the lever 81 mounted on the shaft 81' extending transversely across the frame. The lever 81 is actuated by the cam 82 on the shaft 83. This shaft 83 is connected by the sprocket chain 84 to the shaft 85 which is connected by the gears 86 and 87 to the driving shaft 2, the sprocket chain being arranged on one side of the frame and the gears on the opposite. This driving connection for the oscillating member 75 swings it from a horizontal position shown by dotted lines in Fig. IX, to the vertical position shown therein.

To rock the member 68 from its carton engaging or picking up position as shown by dotted lines in Fig. IX, to its delivery position, as shown by full lines, it is provided

with a segmental gear 88 coacting with a fixed segmental rack 89. It will be obvious that with the segment 88 in engagement with the rack, when the member is swung from its vertical to its horizontal position or vice versa, it is oscillated. The cartons are inverted by this shifter and carried into position to be delivered onto the table 67. To effectively deliver the cartons to the table the flaps 90 thereof are spread out to a horizontal position, as shown in Fig. IX. The flap spreading or opening fingers 91 are pivoted at 92 on the vertically adjustable member 98. This member 98 is mounted for vertical movement in the bracket 93. The member 98 is connected by the link 95 to the lever 96 mounted on the shaft 81', the lever being actuated by a cam 97 on the shaft 83. The member 98 is connected to the link 95 by means of the clip 99 on the lower end of member 98. To spread and collapse the fingers, the inwardly projecting arms 100 thereof are connected to the rod 101 reciprocating in the member 98. See Fig. XI. The arms 100 are slotted at 102 to engage pins 103 on the reciprocating rod 101. The rod 101 is connected by the link 104 to the lever 105 on the shaft 81' actuated by the cam 106 on the shaft 83. By thus arranging the parts, the spreader is first actuated to carry the spreader fingers up within the flaps by the upward movement of the member 98 which is accomplished through the connection described. The fingers are then spread by the upward movement of the rod 101 which is accomplished through its connection described, the movements being properly timed through their driving connections. The cartons are pushed from this position shown in Fig. XII, that is, after the flaps have been spread or bent to a horizontal position onto the table 67. The feed members 107 by which this is accomplished are carried by the slides 108 arranged in suitable ways 109 provided therefor in the table. See Figs. XII, XIII, and XIV. These slides 108 are provided with racks 110 on their under sides, which are driven through the pinions 111 on the shaft 112 arranged below the table. The shaft 112 is driven through the train of gears 113, 114, 115, and the oscillating segment 116 which meshes with the gear 115. The segment 116 is pivoted at 117 on shaft 81'. The segment is provided with an arm 118 having a roller 119 thereon traveling on the cam 120. The table 67 is provided with guides 121 for the cartons, the guides being supported on overhanging arms 122 so that the lower edges of the guides 121 are spaced from the table to permit the flaps to project under the guides. The table 67 is provided with openings 123 at its forward end to which the cartons are delivered through the holders 37.

I have described only one shifter mecha-

nism, one flap spreader mechanism, and one carton feeder, as the other is a duplicate mechanism. The operating connections for the shifter and flap spreader mechanism are 5 duplicate. The two feed or pusher members 107 are actuated through the single cam 120.

The cartons are supported in position above the openings 122 in the feed table by their flaps. From this position, they are 10 pushed through the opening and over the holders 37 by the members 124 mounted to reciprocate on the vertical rods 125 carried by the table 67.

The delivery members 124 are connected 15 by the links 126 to the levers 127 mounted on the transverse shaft 128. These levers are in turn connected by the links 129 to the bent levers 130 mounted on the transverse shaft 131. The bent levers 130 are actuated 20 from the cams 132 acting on the rods 133 arranged to reciprocate in suitable bearings in the brackets 51. The springs 134 on the rods 50 return the packer fingers. The springs 134 on the rods 133 return the 25 plungers to their initial position. As stated, the holders 37 are swung under the openings 122 in the feed table in which position the cartons are pushed over the holders by the members 124. The cartons are then carried 30 by the holders around to the lower position above the delivery conveyer 9 in which position, the trips 64 act upon the pawls 63 releasing the plungers 57 so that the articles in the holders are pushed out or ejected into 35 the cartons which are simultaneously pushed off the holders and onto the conveyer 9. The next actuation brings the emptied holder into position to receive the articles. This completes the cycle of movements of 40 the machine, which are the delivery of articles to be packaged on suitable trays as 5 on the conveyer 6; the transfer of the trays from the conveyer 6 onto the table 21 during which time the articles are picked up 45 from the trays by the scoop 27 and pushed along thereon up the chutes 28 to the packers 46; the discharge of the empty trays from the table 21 onto the return conveyer 7; the delivery of the empty cartons on the 50 conveyers 8, shifting therefrom to the feed table and spreading the flaps and feeding the cartons to the members 124 by which they are pushed onto the holders; the discharge of the charged holders into the cartons 55 as the same are pushed from the holders and the delivery of the filled cartons from the machine by the conveyer 9.

My improved packaging machine is entirely automatic in its operation. The cartons are effectively delivered so that they are 60 not distorted or injured and articles such as described are effectively packaged without injury thereto.

I have illustrated and described my improvements with considerable detail in the

embodiment illustrated. I have not attempted to illustrate or describe various modifications which I contemplate as being possible and practical as such modifications will undoubtedly be readily understood by those skilled in the art to which this invention relates. I desire, however, to be understood as claiming my improvements specifically in the form illustrated as well as broadly within the scope of the appended claims.

Having thus described my invention, what I claim is new and desire to secure by Letters Patent is:

1. In a structure of the class described, the combination with a delivery chute; a shaft; holders open at their outer ends and disposed radially on said shaft; means for rotating said shaft with a step by step movement whereby the holders are successively brought to a horizontal position at the rear end of said chute; a packer oscillating above the rear end of said chute to push the articles into said holders; plungers within said holders; springs by which said plungers are yieldingly supported, said plungers being provided with ratchet bars; pawls coacting therewith whereby said plungers are retained in their depressed position as the holders are filled; means for feeding cartons arranged to deliver the cartons over the holders when the holders are in their upright position; and means for tripping said pawls when the holders are in their inverted position whereby the articles are ejected from the holders into the cartons as the cartons slip from the holders to the delivery conveyer.

2. In a structure of the class described, the combination with a delivery chute; a shaft; holders open at their outer ends and disposed radially on said shaft; means for rotating said shaft with a step by step movement whereby the holders are successively brought to a horizontal position at the rear end of said chute; a packer oscillating above the rear end of said chute to push the articles into said holders; and means for feeding cartons arranged to deliver the cartons over the holders when the holders are in their upright position, the articles dropping from the holders into the cartons as the cartons slip from the holders while in an inverted position, all coacting for the purpose specified.

3. In a structure of the class described, the combination of a feed mechanism; a shaft; holders open at their outer ends and radially disposed on said shaft; means for rotating said shaft with a step by step movement whereby the holders are successively brought to filling position; plungers within said holders; springs by which said plungers are yieldingly supported, said plungers being provided with ratchet bars; pawls coacting therewith whereby said plungers are

retained in their depressed position as the 5
holders are filled; means for feeding cartons arranged to deliver the cartons over the holders when the holders are in their upright position; a delivery conveyer disposed below said shaft; and means for tripping said plunger pawls when the holders are in their inverted position above said delivery conveyer whereby the material is ejected 10 from the holders into the cartons as the cartons slip from the holders.

4. In a structure of the class described, the combination of a shaft; holders open at their outer ends and radially disposed on 15 said shaft; means for rotating said shaft with a step by step movement whereby the holders are successively brought to filling position; a feed mechanism adapted to deliver to the holders while the holders are in 20 their filling position; spring actuated plungers within said holders; detents for said plungers; means for feeding cartons arranged to deliver the cartons over the holders when the holders are in their upright 25 position and means for releasing said plunger detents, all coacting for the purpose specified.

5. In a structure of the class described, the combination with the feeding means 30 comprising a delivery chute; a shaft; holders open at their outer ends and radially disposed on said shaft; means for rotating said shaft with a step by step movement whereby the holders are successively brought to a horizontal position at the end of said chute; a packer oscillating above the rear end of 35 said chute to push the material into said holders; plungers within said holders; springs by which said plungers are yieldingly supported, said plungers being provided with ratchet bars; pawls coacting therewith whereby said plungers are retained in their depressed position as the 40 holders are filled; means for feeding cartons arranged to deliver the cartons over the holders after they are filled; and means for tripping said pawls whereby the material is ejected from the holders into the cartons.

6. In a structure of the class described, 45 the combination with the feeding means comprising a delivery chute; a shaft; holders open at their outer ends and radially disposed on said shaft; means for rotating said shaft with a step by step movement whereby the 50 holders are successively brought to a horizontal position at the end of said chute; a packer oscillating above the rear end of said chute to push the material into said holders; and means for feeding cartons arranged to deliver the cartons over the 55 holders after they are filled.

7. In a structure of the class described, 60 the combination of holders open at their outer ends; a holder filling means; means for actuating said holders with a step by

step movement whereby they are successively brought to filling position; plungers within said holders; springs by which said plungers are yieldingly supported, said plungers being provided with ratchet bars; 70 pawls coacting therewith whereby said plungers are retained in their depressed position as the holders are filled; a carton feed means arranged to deliver cartons over the holders after the holders are filled; and 75 means for tripping said plunger pawls whereby the material is ejected from the holders into the cartons as the cartons are removed from the holders.

8. In a structure of the class described, 80 the combination of holders open at their outer ends; a holder filling means; means for actuating said holders with a step by step movement whereby they are successively brought to filling position; spring 85 actuated plungers within said holders; detents for said plungers; a carton feed means arranged to deliver cartons over the holders after the holders are filled, and means for tripping said plunger detents, all coacting 90 for the purpose specified.

9. In a structure of the class described, the combination of holders open at their outer ends; a holder filling means; means for actuating said holders with a step by 95 step movement whereby they are successively brought to filling position; spring plungers within said holders, said plungers being depressed and retained in their depressed positions as the holders are filled, 100 means for delivering cartons over the holders after the holders are filled; and means for releasing said plungers whereby the material is ejected from the holders into the cartons as the cartons are removed from 105 the holders.

10. In a structure of the class described, the combination of a carton feed conveyer; a carton stop above said conveyer; a shifter member provided with a fixed finger at its 110 outer end adapted to engage the ends of the cartons and pivoted clamping fingers adapted to engage their sides; an oscillating shifter member support having a spindle for said shifter member; a segment on said support; a reciprocating rack coacting with said segment; a segment on said shifter member; and a fixed rack coacting therewith whereby the shifter member is oscillated on its spindle as the spindle is oscillated to and from its horizontal and vertical 115 positions.

11. In a structure of the class described, the combination of a feed table; a carton feed conveyer arranged at the side of said 120 table, the cartons being delivered by said conveyer on their sides with their open ends toward the table; a shifter member provided with carton engaging fingers; an oscillating shifter member; means for oscillating said 125

shifter member on its support as the support is oscillated to and from its horizontal and vertical positions; a flap spreader comprising a vertically reciprocating finger member, fingers pivotally mounted thereon to swing radially, said fingers being provided with inwardly projecting slotted arms; a reciprocating rod having pins thereon engaging said slotted arms of said fingers; 5 means for reciprocating said finger member and said rod timed so that the finger member is actuated to introduce the fingers between the flaps and the rod actuated whereby the flaps are spread to a horizontal position; and a reciprocating feed member 10 adapted to push the cartons from the shifter member to the table.

12. In a structure of the class described, the combination of a feed table; a carton 20 feed conveyer arranged at the side of said table, the cartons being delivered by said conveyer on their sides with their open ends toward the table; a shifter member provided with carton engaging fingers, an oscillating 25 shifter member support; means for oscillating said shifter member on its support as the support is oscillated to and from its horizontal and vertical positions; and a reciprocating feed member adapted to push the cartons 30 from the shifter member to the table.

13. In a structure of the class described, the combination of a feed table having a delivery opening therein; a carton feed mechanism comprising means for supporting the 35 cartons in an inverted position; a flap spreader comprising a vertically reciprocating finger member, fingers pivotally mounted thereon to swing radially; reciprocating rod connected to said fingers; means for reciprocating said finger member and said rod timed so that the finger member is actuated to introduce the fingers into the flaps and the fingers spread to swing the flaps to a horizontal position; a reciprocating feed member 40 adapted to push the cartons from said supporting member across the table to delivery position; carton guides supported in a spaced relation to the feed table to permit the flaps to project thereunder as the cartons travel along on the table to delivery 45 position said cartons being supported in delivery position above the delivery opening by their flaps; carton holders actuated with a step by step movement to bring them under the delivery opening of the table; and a vertically reciprocating member for delivering the cartons from the table to the holders.

14. In a structure of the class described, the combination of a feed table having a delivery opening therein; a carton feed mechanism comprising means for supporting the 50 cartons in an inverted position; a flap spreader, a reciprocating feed member adapted to push the cartons from said supporting member across the table to delivery 55 position.

position; carton guides supported in a spaced relation to the feed table to permit the flaps to project thereunder as the cartons travel along on the table to delivery position, said cartons being supported in delivery position above the delivery opening by their flaps; carton holders actuated with a step by step movement to bring them under the delivery opening of the table; and a vertically reciprocating member for delivering 60 the cartons from the table to the holders. 75

15. In a structure of the class described, the combination of a feed table having a delivery opening therein; a carton feed mechanism comprising means for supporting the 80 cartons in an inverted position; a flap spreader comprising a vertically reciprocating finger member, fingers pivotally mounted thereon to swing radially; a reciprocating rod connected to said fingers; means for reciprocating said finger member and said rod timed so that the finger member is actuated to introduce the fingers into the flaps and the fingers spread to swing the flaps to a horizontal position; a reciprocating feed 85 member adapted to push the cartons from said supporting member across the table to delivery position; said cartons being supported in delivery position above the delivery opening by their flaps; carton holders actuated with a step by step movement to bring them under the delivery opening of the table; and a vertically reciprocating member for delivering the cartons from the table to the holders. 90

16. In a structure of the class described, the combination of a feed table having a delivery opening therein; a carton feed mechanism comprising means for supporting the 95 cartons in an inverted position; a flap spreader; a reciprocating feed member adapted to push the cartons from said supporting member across the table to delivery position, said cartons being supported in delivery position above the delivery opening 100 by their flaps; carton holders actuated with a step by step movement to bring them under the delivery opening of the table; and a vertically reciprocating member for delivering the cartons from the table to the holders. 105

17. In a structure of the class described, the combination of a feed table; a carton feed conveyer arranged at the side of said table, the cartons being delivered by said conveyer on their sides with their open 110 ends toward the table; a shifter member provided with carton engaging fingers; an oscillating shifter member support; means for oscillating said shifter member on its support as the support is oscillated to and from its horizontal and vertical positions; a flap spreader and a reciprocating feed member adapted to push the cartons from the shifter member to the table. 115

18. In a structure of the class described, 120

the combination of a feed table; a carton feed conveyer arranged at the side of said table, the cartons being delivered by said conveyer on their sides with their open ends 5 toward the table; a shifter member provided with carton engaging fingers; an oscillating shifter member support; and means for oscillating said shifter member on its support as the support is oscillated to and from 10 its horizontal and vertical positions.

19. In a structure of the class described, the combination of a feed table; a carton feed conveyer; a shifter member provided with carton engaging fingers; means for 15 actuating said member to pick up the cartons from the feed conveyer and support them in an inverted position; a flap spreader adapted to spread the flaps to a horizontal position while supported by said shifter 20 member; a feed member adapted to push the cartons from the shifter member across the table to delivery position; guides supported in a spaced relation to the table to permit the flaps to project thereunder as the cartons 25 are pushed to delivery position; carton holders; and a member for delivering cartons from the table to the holder.

20. In a structure of the class described, the combination of a feed table; a carton 30 feed conveyer; a shifter member provided with carton engaging fingers; means for actuating said member to pick up the cartons from the feed conveyer and support them in an inverted position; a flap spreader 35 adapted to spread the flaps to a horizontal position while supported by said shifter member; and a feed member adapted to push the cartons from the shifter member to the table.

40 21. In a structure of the class described, comprising a table means for supporting the cartons in an inverted position; a flap spreader comprising a vertically reciprocating finger member, fingers pivotally mounted 45 thereon to swing radially, said fingers being provided with inwardly projecting slotted arms; a reciprocating rod having pins thereon engaging said slotted arms of said fingers; means for reciprocating said 50 finger member and said rod timed so that

the finger member is actuated to introduce the fingers between the flaps and the fingers spread to swing the flaps to a horizontal position; and a reciprocating feed member adapted to push the cartons from said supporting member to the table. 55

22. In a structure of the class described, the combination of a feed table having a delivery opening therein; a carton feed mechanism comprising means for supporting 60 the cartons in an inverted position; a flap spreader adapted to spread the flaps to a horizontal position while the cartons are so supported; a feed member adapted to push the cartons from the said supporting 65 means across the table to delivery position; guides supported in a spaced relation to the table to permit the flaps to project thereunder as the cartons are pushed to delivery position, the cartons being supported in delivery position by their flaps; and a reciprocating member for delivering the cartons. 70

23. In a structure of the class described, the combination of a feed table having a delivery opening therein; a carton feed mechanism 75 comprising means for supporting the cartons in an inverted position; a flap spreader adapted to spread the flaps to a horizontal position while the cartons are so supported; a feed member adapted to 80 push the cartons from the said supporting means across the table to delivery position; and a reciprocating member for delivering the cartons.

24. In a structure of the class described, 85 the combination of a feed table, a carton feed mechanism comprising means for supporting the cartons in an inverted position; a flap spreader adapted to spread the flaps to a horizontal position while the cartons are 90 so supported; and a feed member adapted to deliver the cartons from said supporting means to the table.

In witness whereof, I have hereunto set my hand and seal in the presence of two 95 witnesses.

ORIN A. HANFORD. [L.S.]

Witnesses:

HERBERT L. LARZELERE,
CARL F. SCHMIDT.
